UNITED STATES PATENT OFFICE.

JOHN L. WHITING, OF BOSTON, MASSACHUSETTS.

BRUSH.

SPECIFICATION forming part of Letters Patent No. 271,559, dated January 30, 1883.

Application filed June 1, 1882. (Model.)

To all whom it may concern :

Be it known that I, JOHN L. WHITING, a citizen of the United States, residing at Boston, in the county of Suffolk and State of Massachusetts, have invented certain new and useful Improvements in Brushes; and I do hereby declare that the same are fully described in the following specification and illustrated in the accompanying drawings.

10 This invention relates to an improvement upon the brush secured to me by Letters Patent No. 81,966, dated September 8, 1868. The brush as constructed under said patent has a series of pointed fingers or projections extending out from the butt-end of the handle, the bristles are arranged in the spaces between these fingers, and the mass of bristles thus penetrated by the fingers or projections is enclosed by a straight cylindrical ferrule that is fitted to the butt of the handle. I find that in this and in other brushes the bristles are liable to fall out, and especially those next to the ferrule.

15 It is the object of my present invention to remedy such defect; and to such end my improvement consists in the combination, with the handle having a series of pointed fingers projecting from its butt and inserted into the mass of bristles, of a barrel-shaped metal cylinder formed of a single piece and contracted at its ends, said ferrule thus constructed being applied to the handle so as to extend down to the points of the fingers and to impinge at its lower end upon the bristles surrounding the 20 set of fingers, as illustrated in the annexed drawings, in which—

25 Figure 1 represents a central longitudinal section of a paint-brush made in accordance with my invention; Fig. 2 represents an end view of the handle and ferrule before the bristles are attached thereto; and Fig. 3 represents a perspective view of the barrel or hub shaped ferrule.

Similar letters refer to similar parts wherever 30 they occur on the different parts of the drawings.

In the drawings, A indicates the handle, a' its butt, and a a a the series of pointed fingers or projections extending therefrom into the 35 mass of the bristles B, as in my said patent.

C indicates the sheet-metal barrel or hub shaped ferrule, made with an increased diam-

eter midway between its ends, as shown, and contracted at each end, as represented in Fig. 3, by which means the cemented ends of the 55 mass of bristles B are held very firmly within such ferrule by driving the projections a a a among them, as shown in Fig. 1. This combination of the sheet-metal barrel or hub shaped ferrule C and a series of projections, a a a, on 60 the butt of the handle A is particularly adapted to the manufacture of the larger kinds of brushes, which could not be made practically with a single projection on the butt of the handle combined with a cylindrical ferrule. By 65 the combination of the barrel or hub shaped metallic ferrule C and the series of projections a a a on the butt of the handle A, the latter is more easily driven as compared with a straight or cylindrical ferrule, and as the barrel or hub 70 shaped ferrule C is of increased diameter midway between its ends, the ends of the bristles are allowed to expand freely when the projections a a a are driven among them and expanded against the narrower end of the ferrule, 75 by which the bristles are confined very firmly to the handle and ferrule. It will be seen that the lower end of the ferrule is on a line with the ends of the points or fingers a, so that it will impinge upon the bristles and hold them 80 firmly against the lower portion of the fingers. The bristles spread out somewhat in the space 85 left between the middle of the ferrule and the fingers, so that the bristles will necessarily be more securely retained in place, and it will be evident that cement distributed in said space among the ends of the bristles will, when dry, render it impossible to pull out the bristles. Where the walls of the ferrule are parallel 90 with the fingers, however, as in my said patent, the above object cannot be attained, and the bristles will not be pinched by the lower end of the ferrule, as in the present instance. The ferrule is formed in one piece, and is hence strong and durable.

95 I am aware that a brush has been made with the handle passed through a wooden plug and the lower pointed end of the handle extended out from the plug into the mass of bristles, a ring or thimble being fitted upon the plug and having its lower contracted end adapted to bind upon the bristles between the plug and the pointed end of the handle; but such brush lacks the element of the fingers projecting from

the butt of the brush, which butt I form integral with the handle, and the ring or ferrule does not extend down even with the end of the single point. In another instance the pointed end of the handle has been inserted in the mass of bristles and a barrel-shaped ferrule formed of wire; but the wire is apt to become unwrapped or its coils separated, so as to destroy the efficiency of the brush. Also, a hollow brush-handle has been formed with a barrel-shaped butt, in which the bristles are received, the bristles in such instance being bound by twine. Numerous other brushes have been patented in which the butt-end of the bristles is held by a ferrule—as, for example, the handle has been provided with a tongue, which is inserted in the mass of bristles, and an elastic rubber band sprung over the meeting ends of the handle and bristles. Also, a cylindrical cap provided with points extending below its lower edge has been fitted on a handle and the

bristles fitted in the cap, the points of which enter the mass of bristles; but none of said brushes are constructed as herein shown, described, and claimed.

25

What I claim is—

The herein-described brush, comprising the handle A, formed with butt a', having a series of projections, a a a, which enter the mass of bristles, and the barrel-shaped sheet-metal ferrule C, contracted at its ends and fitted upon the butt of the handle, the lower end of said ferrule pinching the bristles around the set of projections on a line with the outer ends of said projections, as shown, and for the purpose 35 set forth.

30

In testimony whereof I have affixed my signature in presence of two witnesses.

JOHN L. WHITING.
